PRESSURE EXTRACTOR

William J. Asher, Colorado Springs, Colo.

Application November 27, 1931
Serial No. 577,649

16 Claims. (Cl. 100—50)

This invention relates to pressure extractors such as, for example, those of the type adapted for use in laundry work for removing water or other cleaning fluid from articles of apparel and the like after they have been subjected to the washing or cleaning process.

Most of the devices heretofore designed and constructed for this purpose have been of the centrifugal type and have involved large and bulky installations. The few extractors of the positive pressure type which have been developed are of equally large dimensions and are adapted only for commercial use in laundries or other cleaning establishments.

The present invention, on the other hand, contemplates the provision of an extractor of the positive pressure type which is particularly adapted for use in the household, where space is generally at a premium and where the conservation thereof must be given consideration in the designing of any mechanical device or installation for such use.

It is, therefore, one of the objects of the invention to provide a collapsible pressure extractor for household use, the dimensions of which may be reduced when it is not in actual use, so that it may be stored in a small space until again required.

Other and more specific objects of the invention are the provision of novel and improved means for securing the parts of such extractors in extended or retracted positions, for securing the cover to the extractor chamber, for controlling the application of the motive fluid to the power cylinder of the extractor, and for removing the extracted liquid from the device.

Other objects and features of novelty will be apparent from the following specification, when read in connection with the accompanying drawings, in which one embodiment of my invention is illustrated by way of example.

In the drawings:

Figure 1 is a vertical central cross sectional view of a pressure extractor embodying the principles of the invention; the parts being shown in retracted or collapsed position;

Figure 2 is a top plan view of the extractor;

Figure 3 is a horizontal cross sectional view taken on line 3—3 of Figure 1;

Figure 4 is a horizontal cross sectional view taken on line 4—4 of Figure 1; and

Figure 5 is a fragmentary cross sectional view taken on line 5—5 of Figure 1.

Referring particularly to Figure 1 of the drawings, it will be seen that the improved pres-

sure extractor comprises essentially the power or motor cylinder 10, the extractor cylinder 11, and the plunger 12. In the collapsed or retracted position of the device, the parts occupy the positions shown in this figure. It will be understood that, in operation, the extractor cylinder 11 is partially withdrawn or extended from the power cylinder 10 and the plunger 12 is adapted to reciprocate within both of the cylinders in order to compress within the extractor cylinder 11 the articles of apparel or other material from which liquid is to be extracted.

The power or motor cylinder 10 is provided with the cylindrical wall 15, the bottom wall or head 16, and the top head which is formed by the casting 17. The cylindrical wall 15 and the bottom 16 are preferably united by soldering and the head casting 17 may be removably secured to the wall 15 as by means of the screws 18. The head 17 of the power cylinder is provided with the central opening 20 around the margin of which is formed the raised portion 21 which is grooved as at 22 for a purpose to be later described.

The extractor cylinder 11 is adapted to fit slidably within the opening 20 and the complete removal of the cylinder 11 is prevented by the ring 25 which is secured to the lower end, as by means of the fastening element 26, just above the outwardly extending flange 27 formed at the base of the extractor cylinder.

In order to secure the cylinder 11 in its extended or retracted positions with respect to the power cylinder 10, a split ring 30 is provided, the two halves of which are adapted to closely embrace the wall of the cylinder 11 as clearly shown in Figure 4 of the drawings. The split ring 30 is provided with a lower inwardly directed flange 31 which is adapted to enter the groove 22 provided in the raised portion 21 of the head 17 of the power cylinder. The two halves of the split ring 30 are also provided with the perforated lugs 32 through which the bolts 33 are adapted to extend. Upon one end of each of the bolts 33 there is provided a nut 34 which is prevented from turning relatively to the rings 30 by means of a shoulder 35 formed on each end of one of the halves of the ring 30. A washer 36 may be provided between one of the lugs 32 and the shoulder 37 of the bolts, and operating handles 39 are provided at the opposite ends of the bolts from those to which the nuts 34 are applied, for the purpose of rotating the bolts and contracting the split ring 30, whereby the cylinder 11 is firmly clamped in its relatively

63

65

70

75

80

85

90

95

100

105

110

adjusted positions with respect to the power cylinder head 17.

The upper rim of the extractor cylinder 11 is flared outwardly similarly to the bottom flanges 27 as at 40, and the annular member 41 is secured to the cylinder 11 immediately below the flange 40. The annular member 41 is provided with the laterally extending hinge plate 45 provided with the side flanges 46 and the outer end 10 flange 47. A drain opening 48 is provided in the plate 45 at its junction with the annular portion of the member 41. Upstanding lugs 50 are provided on the flanges 46 and are perforated as at 51 for the reception of a pintle member 52.

15 A cover 55 is provided for the extractor cylinder 11 and is preferably formed with a concave undersurface which is provided with the flat marginal rim portion 56 adapted to contact with the flange 40 when the cover is in closed 20 position. The cover 55 has a laterally extending hinge plate 57 which is provided with the downwardly projecting lugs 58 through openings in which the pintle 52 is adapted to extend. It will be readily seen that the hinge plates 45 and 25 57, together with the pintle 52 provide means for pivotally raising the cover 55 from the cylinder 11.

The cover has a depending flange 60 which is provided with the inwardly opening groove 61 which is adapted to receive the expansible locking ring 62. The annular member 41 which surrounds the upper end of the extractor cylinder 11 is provided with the outwardly facing groove 63 into which the expansible locking ring is 35 adapted to move when it is contracted to lock the cover 55 in closed position on the cylinder 11. As will be readily seen in Figure 1 of the drawings, the locking ring 62 is adapted to occupy a portion of both the grooves 61 and 63 when in 40 locked position.

The ends 65 of the locking ring 62 are bent and flared outwardly as shown in Figure 3 and are perforated for the reception of the pins 66 which are adapted to pivotally secure the pairs of 45 arcuate shaped links 67 above and below the ends 65 of the ring. The laterally extending plate 57 of the cover 55 is provided with the hollow boss 70 in which a shaft 71 is adapted to rotate. An operating handle 72 is adapted to be 50 secured to the upper end of the shaft 71 as by means of the peened-over upper ends 73 of the rods 74 which are adapted to pass downwardly through the drilled openings 75 in the shaft 71. The lower ends of the rods 74 are provided with 55 the enlarged cylindrical portions 77 which are adapted to pass through openings in the inner ends of each pair of links 67. The rods 74 are provided with heads 78 for retaining the lower links 67 in position and the links are adapted to 60 be spaced by means of the small sleeves 79 which are adapted to surround the enlarged portions 77 of the rods 74. It will thus be readily seen that by rotating the operating handle 72 to the position shown in Figures 1, 2 and 3, the locking ring 62 will be contracted so as to move into the 65 groove 63 of the ring member 41 and securely lock the cover 55 upon the upper end of the cylinder 11. In this position the handle 72 abuts the stop 80 provided on the boss 70, and when 70 the handle is rotated until the opposite side thereof abuts the stop 81, the ends 65 of the locking ring 62 will be moved further apart and the rings 62 will be expanded out of the groove 63 and the cover may then be raised.

75 The plunger 12 comprises essentially the hol-

low shaft 85, the cup shaped head 86, and the piston member 87. The head 86 and the piston 80 87 may be connected to the shaft 85 by means of cotter pins 88. A slight clearance space 90 is provided between the margin of the head 86 and the inner wall of the cylinder 11 through which the expressed liquid may pass during the operation of the device.

The piston member 87 is provided with the cup leather 92 which is secured to the margin thereof by means of the screws 93, and provides a fluid tight fit between the piston 87 and inner side of the wall 15 of the power cylinder 10.

The mechanism for introducing the motive fluid to the power cylinder and exhausting it therefrom will now be described. An opening 95 is provided in the wall 15 of the power cylinder 10 near the bottom thereof and a fitting 96 is applied to the outside of the wall at this point.

A passageway 97 passes through the fitting 96 and serves to connect the opening 95 with the nipple 98. A drain opening 99 is adapted to be stopped by the screw plug 100 in the lower part of the fitting 96. A combined valve and double T connection 101 is provided 100 with the internally threaded projection 102 which is adapted to be screwed onto the nipple 98.

The member 101 is provided with the threaded ends 104 and 105 for the reception of inlet and outlet hose connections respectively. 105

A frusto-conical valve chamber 107 is provided in the member 101 and the wall of the valve chamber is provided with openings 108, 109, and 110 which communicate respectively with the inlet passageway of the member 101, the fitting 110

96, and the outlet or drain passageway 112 of the member 101. The three-way valve chamber 107 is provided with the rotatable valve member 115 which is adapted to be secured therein by means of the nut 116 threaded upon the pro- 115

jecting end 117 and bearing upon the washer 118 all as clearly shown in Figure 1. The valve body 115 is hollow and is provided with the two openings 120 and 121 spaced 90° apart and 120

adapted to place the openings 108 and 109, or 120 109 and 110 alternatively in communication with each other. It will be readily perceived that when the openings 108 and 109 are placed in 125 communication the pressure fluid will be permitted to flow from the inlet end of the member 101 through the valve and the fitting 96 into the power cylinder beneath the piston 87 and cause the plunger 12 to rise in the extractor cylinder. When the valve is rotated so that the 130 openings 109, 110 are placed in communication, the pressure fluid in the power cylinder is permitted to flow therefrom through the exhaust passageway 112 of the member 101 and the plunger is permitted to descend.

A vertically arranged valve operating shaft 125 is coupled to the upper end of the valve body 115 as at 126 and is connected at its upper end to a member 127 which is adapted to rotate in the bearing 128 provided in the bracket 129

which is adapted to be securely fastened to the upper end of the wall 15 of the power cylinder as at 130. The upper end of the member 127 is squared and is adapted to receive the handle 131 by which the valve is operated. The handle 145

131 may be secured to the member 127 as by means of the screw 133 and washer 134. The hub 132 of the handle 131 is provided with the projection 136 which is adapted to abut the 145

stops 137 and 138 formed on the bracket 129 150

137 and 138 formed on the bracket 129 150

when the valve 115 is in exhaust and admission positions, respectively.

In the operation of the extractor, the extractor cylinder 11 is withdrawn from the power cylinder 10, preferably until the abutment ring 25 engages the inner margin of the opening 20, and the clamping ring 30 is contracted to firmly grip and retain the cylinder 11 in its extended position. The plunger 85 is, of course, initially 5 in the position shown in Figure 1 and when the extractor cylinder 11 is extended, the pressure head 86 of the plunger will be at the bottom of the cylinder 11. The cover 55 of the extractor cylinder is then raised and the material 10 from which the liquid is to be expressed is placed within the cylinder 11 so as to rest upon the pressure head 86. The cover 55 is then secured in place upon the top of the extractor cylinder 11 by the operation of the handle 72 15 which, as has been described, causes the locking ring 62 to engage the annular member 41 of the cylinder 11. The valve 115 is then rotated by means of the handle 131 to admit fluid pressure to the power cylinder beneath the piston 87. This, of course, causes the plunger 85 to 20 rise and the material in the cylinder 11 will be compressed between the concave surfaces of the cover 55 and the pressure head 86. The expressed liquid will flow through the clearance 25 space 90 between the margin of the pressure head 86 and the wall of the cylinder 11 and from thence into the power cylinder 10 above the piston 87. Any liquid which may fall upon the top of the extractor apparatus will flow 30 through the openings 140 in the cylinder head 17 and also be accumulated in this portion of the power cylinder. This waste liquid may be drained from the power cylinder through the opening 141 which is connected by the fitting 40 142 and the vertical pipe 143 to the member 101 whence it is adapted to flow through the outlet end 105.

When the liquid is extracted from the material in the cylinder 11, the valve 115 is turned to 45 exhaust position to release the pressure, the cover 55 is raised, and the pressure again applied beneath the piston 87 whereupon the plunger 85 will force the extracted material out at the top of the cylinder 11. This movement 50 of the plunger also serves to elevate the waste liquid in the power cylinder so that it may flow out through the opening 141 as previously described. Then the valve is turned to released position and the plunger 85 is permitted to 55 descend.

In order to avoid marking or injuring a bath tub or other receptacle when the extractor is used therein and to deaden the noise and absorb shocks incidental to transporting the extractor, an annular base member 145 is provided which is preferably constructed of rubber or a similar durable resilient material and is provided with the inwardly projecting flange 146 60 and the side wall 147. The side wall 147 is extended outwardly as at 148 to enclose the fitting 96 and is perforated as at 149 to afford access to the drain plug 100.

Although any convenient source of pressure or motive fluid may be placed in communication with the inlet end 104 of the member 101, it is preferred to employ the ordinary city water as the motive fluid which, at, a pressure of 60 70 pounds per square inch in a 10 inch power cylinder would yield a pressure of 240 pounds to

the square inch upon the material in an extractor cylinder of a diameter of 5 inches.

Finally, when the extracting operations are completed, the extractor may again be collapsed by releasing the clamping ring 30 and causing the cylinder 11 to telescope with the power cylinder 10 and again assume the position shown in Figure 1, whereupon the clamping ring 30 may again be tightened to retain the cylinders in this collapsed position.

The term "collapsible" as employed in the following claims is intended to mean capable of being, by design or intention, reduced to a more compact form as for convenience in transportation or storage, and has no application to any phase of operation of the device in performing its pressing or extracting functions.

Having thus described the invention, what is claimed as new and desired to be secured by Letters Patent is:

1. In a pressure extractor of the class described, in combination, a power cylinder, an extractor cylinder, one end of said power cylinder being provided with an opening adapted to slidably receive said extractor cylinder, a split collar carried by the rim of said opening and adapted to be contracted to firmly grip and retain said extractor cylinder in extended and retracted positions.

2. In a pressure extractor of the class described, in combination, a power cylinder, an extractor cylinder, the head of the power cylinder being provided with an opening in which said extractor cylinder is adapted to be slidably received, outwardly extending flanges provided at the top and bottom of said extractor cylinder for limiting the inward and outward movements respectively of said extractor cylinder, and clamping means associated with the margin of said opening for locking said cylinders in adjusted relative positions.

3. A pressure extractor for laundry purposes or the like, comprising, in combination, an extractor cylinder; a power cylinder, and a plunger, a pressure head formed on said plunger and adapted to reciprocate in said extractor cylinder, and a piston formed on said plunger and adapted to reciprocate in said power cylinder, said power and extractor cylinders being of different diameters and relatively movable, one within the other, for the purpose of collapsing the extractor as for transportation or storage.

4. In a pressure extractor of the class described, in combination, a power cylinder, an extractor cylinder telescoping within said power cylinder, and means for locking said cylinders in adjusted positions relative to each other.

5. In a pressure extractor of the class described, in combination, a power cylinder, an extractor cylinder, and a plunger, the head of the power cylinder being provided with a central opening in which said extractor cylinder is adapted to be slidably received, an annular member adapted to surround the upper margin of said extractor cylinder and to provide an abutment for limiting the movement of said extractor cylinder into said power cylinder, a cover for said extractor cylinder, hinge elements carried by said annular member and said cover, and a pintle connecting said elements for pivotal movement.

6. In a pressure extractor of the class described, in combination, a power cylinder, an extractor cylinder, and a plunger, the head of the power cylinder being provided with a central

- opening in which said extractor cylinder is adapted to be slidably received, an annular member adapted to surround the upper margin of said extractor cylinder and to provide an abutment for limiting the movement of said extractor cylinder into said power cylinder, a cover for said extractor cylinder, hinge elements carried by said annular member and said cover, and a pintle connecting said elements for pivotal movement, and means for locking said cover in closed position.
7. In a pressure extractor of the class described, in combination, a power cylinder, an extractor cylinder, and a plunger, the head of the power cylinder being provided with a central opening in which said extractor cylinder is adapted to be slidably received, an annular member adapted to surround the upper margin of said extractor cylinder and to provide an abutment for limiting the movement of said extractor cylinder into said power cylinder, a cover for said extractor cylinder, hinge elements carried by said annular member and said cover, and a pintle connecting said elements for pivotal movement, means associated with said annular member for locking said cover, and a head on said plunger adapted to reciprocate in said extractor cylinder, said head and said cover being provided with cooperating concave faces between which material may be compressed to retract the liquid therefrom.
8. In a pressure extractor of the class described, in combination, a power cylinder, the head of which is provided with a central opening, an extractor cylinder adapted to be slidably received within said opening, a plunger, a head on said plunger which is adapted to reciprocate with a marginal clearance within said extractor cylinder, and to cooperate with the outer closed end of the extractor cylinder to compress the material from which the liquid is to be extracted, a piston on one end of said plunger adapted to reciprocate within said power cylinder, and means for controlling the admission of pressure fluid to said power cylinder to actuate said plunger.
9. In a pressure extractor of the class described, in combination, a power cylinder, the head of which is provided with a central opening, an extractor cylinder adapted to be slidably received within said opening, a plunger, a head on said plunger which is adapted to reciprocate within said extractor cylinder, and to cooperate with the outer closed end of the extractor cylinder to compress the material from which the liquid is to be extracted, a clearance space being provided between the margin of said plunger head and the wall of said extractor cylinder through which the expressed liquid may pass, a piston on one end of said plunger adapted to reciprocate within said power cylinder, means for controlling the admission of pressure fluid to said power cylinder to actuate said plunger, the inner end of said extractor cylinder being provided with an opening through which the liquid expressed from said material through said clearance space is adapted to pass into said power cylinder, and means for draining said liquid from said power cylinder.
10. In a pressure extractor of the class described, in combination, a power cylinder, the head of which is provided with a central opening, an extractor cylinder adapted to be slidably received within said opening, a cover adapted to be applied to the outer end of said extractor cylinder, a plunger, a head on said plunger which is adapted to reciprocate within said extractor cylinder and to cooperate with said cover to compress the material from which the liquid is to be extracted, the cooperating faces of said cover and said head being concave, a slight marginal clearance space being provided between said plunger head and the wall of said extractor cylinder through which the expressed liquid may pass, a piston on one end of said plunger adapted to reciprocate within said power cylinder, means for controlling the admission of pressure fluid to said power cylinder to actuate said plunger, the inner end of said extractor cylinder being open whereby said liquid may pass to said power cylinder upon the outer side of said piston, said head and other portions of said extractor being provided with drainage openings for collecting waste liquid in the same space within the power cylinder, and means for draining said liquid from said power cylinder.
11. In a pressure extractor of the class described, in combination, a power cylinder, an extractor cylinder, and a plunger having a head adapted to reciprocate within said extractor cylinder, and a piston adapted to reciprocate within said power cylinder, an opening in the wall of said power cylinder near the base thereof for the admission of a pressure fluid thereto beneath said piston, inlet and outlet connections applied to said power cylinder at said opening, a three-way valve controlling the flow of pressure fluid through said connections, a vertical valve operating rod extending upwardly alongside of said power cylinder, a bracket secured to the upper portion of said power cylinder and providing a bearing in which said rod is adapted to rotate, an operating handle on the upper end of said rod, and stops on said bracket against which said handle is adapted to abut in the opened and closed positions of said valves.
12. In a portable, collapsible pressure extractor of the class described, in combination, a power cylinder, an extractor cylinder, adapted to telescope within said power cylinder when not in use, and a plunger having a head adapted to reciprocate within said extractor cylinder and a piston adapted to reciprocate within said power cylinder, an opening in the wall of said power cylinder near the base thereof for the admission of a pressure fluid thereto beneath said piston, a three-way valve adjacent said opening and controlling the flow of pressure fluid into and out of said power cylinder, a valve actuating handle associated with the upper portion of said power cylinder, and operative connections disposed adjacent the wall of said power cylinder between said handle and said valve.
13. A collapsible pressure extractor for laundry purposes or the like comprising in combination, a power cylinder and an extractor cylinder telescoping within said power cylinder, the outer end portions of each of said cylinders forming the extremities of the extractor device.
14. A collapsible pressure extractor for laundry purposes or the like comprising in combination, a power cylinder, an extractor cylinder telescoping within said power cylinder, the outer end portions of each of said cylinders forming the extremities of the device, means for retaining said cylinders in an expanded condition and means for releasing said retaining means so

that said extractor may be collapsed as for the purposes of storage or transportation.

15. A collapsible pressure extractor for laundry purposes or the like comprising, in combination, power and extractor cylinders, means connecting said cylinders for telescoping movement and adjustment one within the other, the outer one of said cylinders providing the sole supporting means for the inner cylinder when 10 said cylinders are in collapsed condition and also in all extended positions thereof, the outer end portions of each of said cylinders forming

the extremities of the extractor device at all times.

16. A portable collapsible pressure extractor unit comprising, in combination, a power cylinder, an extractor cylinder telescoping within said power cylinder, said cylinders being adjustable with respect to each other so as to vary the over-all length of said extractor unit, and a plunger member operatively associated with said cylinders.
